UNITED STATES PATENT OFFICE.

BOZIL S. ROY, OF WORCESTER, MASSACHUSETTS.

DESIGN FOR A CARD-GRINDING MACHINE.

SPECIFICATION forming part of Design No. 13,888, dated May 1, 1883.

Application filed November 27, 1882. Term of patent 14 years.

To all whom it may concern:

Be it known that I, BOZIL S. ROY, of Worcester, in the county of Worcester and State of Massachusetts, have invented and produced a new and original Design for Card-Grinding Machines, of which the following is a description sufficiently full, clear, and exact to enable others skilled in the art to which it appertains to make and use the same, reference 10 being had to the accompanying drawing, which forms a part of this specification, and represents a perspective view of my design.

The distinctive features of my design are the peculiar form and arrangement of the 15 frame, and the relative location in connection therewith of the operative parts to give a symmetrical, ornamental, and appropriate appearance or style to the machine. The end frames are made with uprights *a* at the angles and 20 horizontal transoms *b* *c*, forming open rectangular panels. Horizontal beams *d* and *e* connect the ends at heights corresponding with the transoms *b* and *c*. The upper portions of the end frames have feet resting on the level

of the beams *e*, and are formed with uprights *a'*, horizontal tops *g*, and arched portions *h*, springing from the side uprights, and connecting with the top rail, *g*, at its center by the 25 upper rectangular panels, as shown. The shafts *j* and *k* are respectively located at central 30 positions on the upper and lower transoms, the whole producing a uniform design of very neat and pleasing appearance, and of well-balanced proportions appropriate to machines for 35 the purpose specified.

What I claim, and desire to secure by Letters Patent, is—

The design for a card-grinding machine, embracing the forms and appearance herein 40 shown and described.

Witness my hand this 16th day of November, A. D. 1882.

BOZIL S. ROY.
